UNITED STATES PATENT OFFICE.

ERNEST B. NIEMANN, OF CUMMINGS, KANSAS.

REIN-GUARD.

1,148,530.

Specification of Letters Patent. Patented Aug. 3, 1915.

Application filed May 9, 1914. Serial No. 837,492.

To all whom it may concern:

Be it known that I, ERNEST B. NIEMANN, citizen of the United States, residing at Cummings, in the county of Atchison and 5 State of Kansas, have invented certain new and useful Improvements in Rein-Guards, of which the following is a specification.

This invention relates to attachments for horse drawn vehicles, and more particularly 10 to a device for supporting the driving reins and preventing the same from becoming entangled in the doubletree and swingletrees, and has for its object the simplification of the construction and arrangement of the 15 parts in devices of this class heretofore invented.

With the above and other objects in view, the preferred form of the invention resides 20 in the construction and arrangement of parts as set forth and claimed in the specification and appended claims.

In the accompanying drawings:—Figure 1 is a perspective view showing the preferred form of my invention applied to a 25 double tree. Fig. 2 is a transverse sectional view of the same.

Referring more particularly to the drawings, the numeral 1 indicates the usual draft pole or shaft having the usual arms or 30 hounds 2 extending therefrom.

The numeral 3 indicates the doubletree secured to the shaft or pole 1 by means of the bolt 4, said bolt 4 being secured in a block 5 through which the shaft 1 passes. 35 The doubletree 3 is provided with the usual swingletrees 6.

The rein holder, comprising an embodiment of my invention, is formed preferably from a single strand of wire 7, having the 40 intermediate portion 8 thereof substantially parallel to the doubletree 3. The said strand of wire 7 is bent adjacent its ends and at the points 9 and 10 to form portions 11 and 12 extending rearwardly of the intermediate portion 8 and at substantially right angles thereto. The said portions 11 are in turn bent to form portions 13 and 14, said portions 13 and 14 extending downwardly and at right angles to the said portions 11, said portions 13 and 14 being bent at substantially right angles to form portions 15 and 16 terminating in and secured to plates 17 and 18, said plates 17 and 18 being secured in any suitable means to the rear face of 50 the doubletree 3. It will thus be seen that the portions 11, 12, 13, 14, 15 and 16 pro-

vide a substantially U-shaped portion for supporting the intermediate portion of the wire in spaced relation to the doubletree 3 and the swingletrees 6.

The operation of the device is thought to be clearly understood from the description and drawings, and it will be readily appreciated by any one who is familiar with devices of this class that the position in which 60 my invention is applied to a doubletree and the form of the same is a simple though vast improvement over devices of this class heretofore invented. The object in supporting the same from the rear face of the double 65 tree 3 is that there is no possible way in which the invention may interfere with the connecting of the horse to the swingletrees 6.

It will be noticed that the portions 11 and 12 are slightly longer than the portions 15 and 16, thereby serving to place the intermediate portion 8 of the rein holder slightly in advance of the double tree 3, thereby preventing engagement of the reins with the same or with the swingletrees 6.

The forming of the wire with substantially U-shaped portions adjacent its end and securing the same to the rear face of the doubletree, facilitates the securement of the device to any type of doubletree regardless 85 of the position of the swingletrees upon the doubletree. It is well known that in some cases the swingletrees are pivoted on the doubletree, and it will thus be seen that my invention would be as readily applicable to 90 this type of draft gear as to the type shown in my drawings. The fact that the distance that the vertical portion 13 is from the doubletree 3 would allow of ample space 95 for the swinging of a swingletree of the pivoted type, and would therefore no more interfere with the free operation of a swingletree of the above-mentioned type and the one shown in the drawings. The fact that my invention is preferably formed of 100 one single strand of wire serves to simplify the same and tends toward a cheapness of construction.

While I have shown a specific form in the drawings, still it will be understood that I 105 may make such minor changes in the detail structure which shall not depart from the spirit of my invention.

What I claim and wish to secure by Letters Patent is:—

1. A rein holder formed from a single strand of wire, provided adjacent its ends

- with substantially U-shaped supporting portions, one of the arms of said portions being longer than the other arms of said portions, the shorter of the said arms of the 5 U-shaped portions being secured to the rear face of a doubletree, whereby to dispose the U-shaped portions remote from the swingletrees and the rein guard in advance of the doubletree.
- 10 2. A rein holder formed of a single strand of wire, provided with U-shaped portions on each end thereof, said U-shaped portions serving to support the rein holder from the rear face of a doubletree and the inter-

mediate portion of the rein holder lying 15 parallel with and slightly in advance of the longitudinal axis of the doubletree to prevent any contact of the driving reins with the swingletrees, said U-shaped portions allowing of free movement of the swingletrees upon the doubletree.

In testimony whereof I affix my signature in presence of two witnesses.

ERNEST B. NIEMANN.
